UNITED STATES PATENT OFFICE.

WILHELM G. DANIELSEN AND WILLIAM MERRILL, OF RICHMOND, UTAH;
SAID MERRILL ASSIGNOR TO SAID DANIELSEN.

SULKY-PLOW.

SPECIFICATION forming part of Letters Patent No. 605,085, dated June 7, 1898.

Application filed May 6, 1897. Serial No. 635,383. (No model.)

To all whom it may concern:

Be it known that we, WILHELM G. DANIELSEN and WILLIAM MERRILL, citizens of the United States, residing at Richmond, in the county of Cache and State of Utah, have invented a new and useful Sulky-Plow, of which the following is a specification.

This invention relates to sulky-plows, and has for its object to provide a light and durable plow-frame of novel construction mounted upon the carrying-wheels, which are independently adjustable up and down for adapting the plow to hillside work.

Another aim of the invention is to provide means for counteracting the lateral pressure of the landside and easing the draft of the plow; also, to provide a combined brake and scraper operated by means of a foot-lever under control of the driver.

Other objects and advantages of the invention will appear in the course of the subjoined description.

The invention consists in an improved sulky-plow embodying certain novel features and details of construction and arrangement of parts, as hereinafter fully described, illustrated in the drawings, and incorporated in the claims.

In the accompanying drawings, Figure 1 is a perspective view of a sulky-plow constructed in accordance with the present invention. Fig. 2 is a detail horizontal section of the same. Fig. 3 is a detail vertical cross-section showing the plowshare, its standard, the trailing wheel, and adjacent parts. Fig. 4 is a detail perspective view showing the foot-lever, a portion of the scraper, and the interposed connection. Fig. 5 is a detail plan view of the axle on which the trailing wheel is journaled.

Similar numerals of reference designate corresponding parts in the several figures of the drawings.

Referring to the drawings, 1 designates the plow-beam, which is composed of spaced channel-beams 2, having their webs arranged nearest each other and their flanges extending in opposite directions. These channel-beams are securely bolted together at their front and rear ends and at intermediate points, if desired, and upon one side of the beam thus

constructed is secured an angular brace 3, forming a part of the plow-frame.

4 is a clevis at the forward end of the plow-beam.

The carrying-wheels 5 are mounted on a divided axle and arranged one in front or in advance of the other. The inner ends of the two parts of the axle are mounted in bearings attached to the beam 1 and brace 3 and are arranged in parallel relation to each other. The forward section of the axle is provided at one side of the frame with a forwardly-extending crank-arm 6, upon which one of the wheels is journaled, and the rear section of the axle is provided upon the opposite side of the frame with a rearwardly-extending crank-arm 7, on which the other carrying-wheel is journaled. A thumb latch-lever 8 is rigidly secured to the rear section of the axle inside of the crank-arm 7 and engages with a toothed segment 8^a, whereby the wheel on that side may be raised or lowered for the purpose of elevating or lowering that side of the plow-frame. The other or front section of the axle 75 is provided inside of the crank-arm 6 with a rigid crank 9, from which a link 10 extends rearward and connects pivotally with another thumb latch-lever 11, engaging a toothed segment 12, secured to the plow-beam near its rear end. By means of the last-named thumb latch-lever the wheel on that side of the machine may be raised or lowered, or, rather, the frame at that side may be elevated or depressed, the object being to enable the plow-frame to be maintained in a level position while being operated on a hillside.

13 designates the plow-standard, which is secured at its upper end between the rear ends of the channel-beams 2 and which has 90 the plowshare 14 rigidly attached to its lower end.

15 denotes a wheel arranged in rear of the plow and having a beveled rim or periphery 16. This wheel is journaled upon an inclined axle 17, on the rear end of an arm 18, which extends forward and is bent to pass in advance of said wheel, where it is secured at its forward end between clamping-blocks 19, secured to the outer side of the standard by 100 means of a U-shaped clip 20, surrounding said blocks and having its ends inserted

through openings in the standard and secured upon the opposite side by nuts. The arm 18 is also connected with the moldboard of the plow by means of a brace 21, having a U-shaped clip 22 embracing said arm. The axle 17 passes through the wheel 15, and the latter is held in place by means of a cotter-pin 23, passing through the axle. To the inner side of the wheel 15 is secured a cap 24, which fits over the end of the axle and is provided with a circumferential flange 25, perforated to receive fasteners, such as screws, by means of which the cap is secured to the wheel. The interior of the cap 24 is sufficiently large to permit the turning of the cotter-pin without interference, and also forms an oil-cup, in which a supply of oil may be placed for lubricating the axle. When the side pressure is applied to the wheel 15 in the operation of the plow, the end of the axle 17 bears against the inside of the cap 24, thus affording a minimum amount of resistance.

26 designates a rearwardly-projecting arm which is secured at its forward end to the rear end of the plow-beam and extends over the wheel 15. Pivotaly connected to the rear end of said arm is a depending bar 27, constituting a combined brake and scraper, the same bearing at its lower end against the beveled rim or periphery of the wheel 15 and having its lower end or shoe portion bent into L shape, so as to embrace the inside edge of said wheel. From an intermediate point on the bar 27 a link or rod 28 extends forward and connects to a short crank-arm 29 on a transverse rock-shaft 30, journaled on the plow-beam, and having at its inner end a foot-lever 31, arranged within reach of the driver's foot while sitting on the machine. The driver by placing his foot upon the lever 31 may thus press the combined brake and scraper against the wheel 15 with any desired force.

By means of the construction above described a very simple, cheap, and light sulky-plow frame is obtained, and the same may be always maintained in a level position by means of the provision made for adjusting the carrying-wheels up or down. The wheel 15 by reason of its inclined position counteracts the tendency of the landside to press inward, and thereby greatly eases the draft of the plow.

It will be understood that the construction

described is susceptible of changes in the form, proportion, and minor details, which 55 may accordingly be resorted to without departing from the spirit or sacrificing any of the advantages of this invention.

Having thus described the invention, what is claimed as new is— 60

1. In a sulky-plow, the combination with the plow-frame and its carrying-wheels, of the plow-standard connected rigidly thereto, the plow attached rigidly to said standard, a wheel arranged in rear of said plow and 65 mounted upon an inclined axle, and a hollow cap secured to said wheel and inclosing the end of said axle, said cap being arranged to bear against the end of the axle for taking the lateral thrust on said wheel, and also constituting an oil-cup, substantially as described. 70

2. In a sulky-plow, the combination with a share-carrying standard, of a presser-wheel having a beveled rim, an inclined angular hanger arranged to extend in front of the presser-wheel and provided at its rear extremity with a transverse inclined axle on which the presser-wheel is mounted, and a clamp attached to the standard and engaging 75 with the front part of the hanger to hold the latter rigidly on the standard, substantially as described. 80

3. In a sulky-plow, the combination with a frame and a plowshare, of a hanger attached 85 to the frame and provided with a transverse axle, an inclined landside pressure-wheel journaled on the axle of said hanger, a supporting-arm attached to the frame and extending rearwardly therefrom over the landside pressure-wheel, a scraper hung on the supporting-arm, a treadle-shaft journaled on the plow-frame and provided with a crank-arm, and a pitman connected to the crank-arm of said treadle-shaft and to the scraper, 90 for the purpose described, substantially as set forth. 95

In testimony that we claim the foregoing as our own we have hereto affixed our signatures in the presence of two witnesses.

WILHELM G. DANIELSEN.
WILLIAM MERRILL.
